UNITED STATES PATENT OFFICE.

SAMUEL H. HARRINGTON, OF NEW YORK, N. Y., ASSIGNOR TO WILLIAM C. WILSON, OF NYACK, NEW YORK.

RAILWAY SAFETY DEVICE.

No. 927,041.

Specification of Letters Patent.

Patented July 6, 1909.

Application filed March 29, 1904. Serial No. 200,563.

To all whom it may concern:

Be it known that I, SAMUEL H. HARRINGTON, residing at New York, in the county of New York and State of New York, have invented certain new and useful Improvements in Railway Safety Devices, of which the following is a full, clear, and exact description, such as will enable others skilled in the art to which it appertains to make and use the same.

This invention relates to railway safety devices.

One of the objects thereof is to provide an automatic safety appliance such as will insure the effectiveness of a danger signal.

Another object is the provision of apparatus whereby any danger signal will leave a distinctive mark upon any car or train attempting to run past the same.

Other objects will be in part obvious and in part hereinafter pointed out.

The invention proposes, broadly, the suspension at a semaphore or other signal of a printing device of distinctive configuration peculiar to that signal and adapted when the signal is in "danger" position to coöperate with recording surfaces carried by cars and leave an impression upon the recording surface of any car attempting to pass the signal of the distinctive number or symbol of the same. Also, it is proposed to utilize the mutual reaction of the printing device and the recording surface with which it contacts to apply the brakes of the car and notify the train despatcher or other person that the signal has been passed.

The invention accordingly consists in the features of construction, combinations of elements and arrangement of parts which will be hereinafter described and the scope of the application thereof indicated in the claims.

In the accompanying drawings which show one embodiment of my invention, various others of which will be readily suggested:—

Figure 1 is an elevation of the safety mechanism constructed in accordance with this invention, in operative position, showing the relation thereto of the parts carried by the car. Fig. 2 is a similar view showing the parts in inoperative position. Fig. 3 is a view of a rolling member or carriage with a part of the lever upon which it is adapted to roll. Fig. 4 is a detail view of an electric call box with the associated parts. Fig. 5 is an elevation of the plate carried by a car before

contact with the printing device. Fig. 6 is an end elevation of the same after contact. Fig. 7 is a view showing a preferred arrangement of balls arranged to outline various symbols which may designate the several numerals associated therewith.

Similar reference characters refer to similar parts throughout the several views.

Referring now to Fig. 1, A represents a post or support upon which is mounted 65 semaphore B. By the word "semaphore" as used throughout this description and the following claims is meant any danger signal the operation of which involves mechanically moving parts. This semaphore is actuated 70 in accordance with the operation of any desired system of signaling, not described herein as it forms no part of the present invention.

Pivotedly mounted upon support A by means of a bracket 1 is a lever 2. The word 75 "lever" as used throughout this specification and in the following claims is used broadly to designate a lever of any class, that is, irrespective of the relative positions of fulcrum, weight and power, and also irrespective of 80 whether it is a rigid member or a flexible member held rigid by weights or other means. The inner end of said lever, that is, the end toward support A, is adapted to be given a limited vertical movement by the semaphore, it being depressed when the latter is in a position indicating "safety" and permitted to rise upon the semaphore assuming a "danger" position. With the common type of 85 semaphore shown in Figs. 1 and 2, an eccentric 3 is rigidly mounted upon the arm thereof at the pivotal point and is adapted to coact with an upwardly disposed, inwardly curved arm 4 firmly secured to the inner end of lever 2. This eccentric is given such an 90 angular position with reference to the semaphore arm that upon the latter assuming a horizontal position, customarily denoting danger, the eccentric will permit arm 4 to rise and, conversely, upon the falling of the 95 semaphore arm, arm 4 will be depressed.

Mounted upon the outer arm of lever 2 and adapted to roll upon the same between collars 2^a and 2^b is a carriage C. This carriage is formed of two side members 5 adjustably 105 secured at the bottom by means of bolts 6 and joined at the top by rollers 7. The faces of these rollers are grooved with a radius of curvature equal to that of the round outer arm of lever 2 and the side members are bent 110

so as to inclose this arm without contact therewith. It will thus be seen that the carriage C is adapted not only to travel along this arm but also to have a rotary movement 5 about the axis thereof. One of the side members 5 projects in a longitudinal direction beyond the other side member forming a shoulder 8 for a purpose hereinafter explained.

10 Suspended from carriage C is a printing device, preferably formed of a plurality of hollow rubber balls 9 each of which is perforated, as shown at 10. The preferred means of suspension is by heavy flexible wires 15 clamped between the members 5 of carriage C by means of bolts 6. Balls 9 contain some pigment preferably composed of lampblack and oil, though obviously any other marking means could be employed. The openings 10 are filled with wicking or waste, or other means whereby the marking fluid may be transmitted to the recording surface. The lower balls on each wire are given sufficient weight to insure the operation of the coöperating parts hereinafter described. The balls 20 at each semaphore are arranged in a distinctive outline. As the number of semaphores may be large, it has been found expedient to arrange the balls to represent numerals in accordance with an arbitrary code, and that 25 shown in Fig. 7 has been found to be peculiarly adapted for this purpose owing to the absence of curves and inclined lines and the essentially different character of the symbols 30 formed.

35 Pivottally mounted upon a car D is a plate 11. By the word "car" is meant any vehicle adapted to travel in a fixed path. The roof of an electric car or cab of a locomotive 40 has been found to be peculiarly adapted for the mounting of this plate. Plate 11 is preferably perforated, as shown at 12, to reduce the wind pressure against the same and provided with corrugations 13 for stiffening purpose. 45 Poses and is given a smooth outer surface adapted to receive and retain an impression from the printing balls 9. Closely adjacent the plate 11 is located a valve 14 in the piping 15 of the air braking system and the lever 16 50 of this valve is normally in engagement with and adapted to be actuated by a lever 18 fixed upon the shaft 19 of the plate. It will thus be seen that upon the oscillation of plate 11 the shaft 19 will be rotated within 55 bearings 20 and by means of levers 18 and 16, the valve 15 will be opened, permitting the escape of air from the braking system and thus applying the brakes. Various other means of applying the brakes by means of 60 the movement of plate 11 will be readily suggested and the above construction is described as merely illustrative of one manner of accomplishing this object.

65 There is preferably mounted upon bracket 1 at a point near the pivot of lever 2 a call

box 21. The preferred construction of this call box forms no part of the present invention and may be of any desired type wherein a distinctive call is electrically sent to a distant station upon the actuation of the crank 70 thereof. Longitudinally journaled within the lever 2 is a shaft 22 having fixed thereto an arm 23 upwardly projecting through an opening in lever 2 and adapted to engage the actuating crank of call box 21. Fixed to the 75 outer end of shaft 22 is a downwardly projecting arm 24 adapted to engage the before-mentioned shoulder 8 upon the side member of the carriage C.

The operation of this embodiment of my 80 invention is as follows:—With the parts in normal "safety" position as shown in Fig. 2, upon the actuation of the semaphore B to danger position, indicated in Fig. 1, the eccentric 3 above arm 4 is raised. The greater 85 weight of the outer arm of lever 2 with carriage C causes this arm to fall as far as is permitted by eccentric 3 and arm 4 and this movement changes the downward inclination of the lever from an inward to an outward direction, referring as before to support A. Carriage C, as a result of this change, moves from its normal position against shoulder 2^a to a position against shoulder 2^b, the 90 shock of contact thereof being lessened, if 95 desired, by a coiled spring 25. In its outer position the carriage C suspends balls 9 directly in the path of plate 11 carried by the car for which the signal is set. Should the signal be disregarded and the car attempt to 100 run past the same, the balls 9 will come into contact with the upper portion of plate 11, leaving their distinctive mark thereon and rotating the plate into a horizontal plane, as indicated in Fig. 6. This movement, on account of the before-described relation of levers 18 and 16, will also result in the application 105 of the brakes upon the car or train. Also, the reaction of plate 11 upon balls 9 will cause carriage C to be swung about the 110 axis of lever 2 in such manner that the shoulder 8 will engage arm 24, and, by means of shaft 22 and arm 23, actuate call box 21 and send a notification to the train despatcher's 115 office or other desired destination to the effect that the danger signal has been passed. The apparatus then falls again into operative 120 position so that a following car would cause a repetition of the above series of operations. Upon the returning of the semaphore to a 125 safety position the carriage C will automatically roll inwardly against shoulder 2^a and out of the path of the plates 11.

It will thus be seen that I have provided a simple, inexpensive and reliable safety device which is entirely automatic in action and does not depend in any way upon the coöperation of the engineer. Also, the fact that a danger signal has been passed will be conclusively evidenced by the plate upon the car, 130

which will indicate not only this fact but will also show which danger signal was passed. The train despatcher, moreover, through the medium of call box 21, will be immediately notified that a danger signal has been passed and will know from the distinctive call which danger signal has been passed, and may act accordingly. The call box, moreover, may be used independently from the remainder of the safety apparatus, as it may be manually actuated by a member of the train crew and a message thus sent to the train despatcher. Another marked advantage of this system is that it may readily be applied with small and inexpensive alterations to various types of systems now in use.

Various changes and modifications will readily be suggested in the above embodiment of my invention. For example, the valve 14 may control the admission of live steam or compressed air to positively apply the brakes instead of releasing the air from the braking system of the type now in general use. Another manifest modification would be the substitution of a wire or wires held taut across the track and provided with stops for the form of lever shown in the drawings. One end of such wire could be raised and lowered in accordance with the movement of the semaphore arm. Also, the recording mechanism may obviously be located within the car and merely the actuating means therefor exposed to the weather. It will also be readily seen that various features of my invention have an independent value, as the braking feature, the printing apparatus and the call box mechanism may be used separately or in any combination one with another. For these and other reasons I desire all features of construction set forth in this description and the accompanying drawings to be interpreted as illustrative and not in a limiting sense. I desire it also to be understood that the language used in the claims is intended to cover both the generic and specific features of the invention which as a matter of language might be said to fall therebetween.

Having described my invention, what I claim as new and desire to secure by Letters Patent is:—

1. In a device of the class described, in combination, a semaphore, a support for the same, a lever pivoted upon said support, and adapted to be operated by said semaphore, a car, and means mounted upon said lever adapted to co-act with a member mounted upon said car.

2. In a device of the class described, in combination, a semaphore, a support for the same, a lever pivoted upon said support, and an eccentric carried by said semaphore adapted to actuate said lever.

3. In a device of the class described, in combination, a semaphore, a support for the

same, a lever pivoted upon said support, an arm on said lever, and an eccentric carried by said semaphore adapted to co-act with said arm and actuate said lever.

4. In a device of the class described, in combination, a car, a movable member, and a carriage mounted thereon and adapted to move thereon into and out of the path of travel of a member mounted upon said car.

5. In a device of the class described, in combination, a lever, a carriage mounted thereon and adapted to roll thereon to the outer end thereof as said end is depressed and to a position adjacent the fulcrum as the outer end is raised, and signaling means mounted upon said carriage.

6. In a device of the class described, in combination, a lever pivoted to a semaphore support, and a carriage mounted thereon and adapted to roll thereon to the outer end thereof as said end is depressed and to a position adjacent the fulcrum of said lever as the other end is raised.

7. In a device of the class described, in combination, a carriage, a printing device suspended therefrom, a car, and means upon said car adapted to co-act with said printing device and receive an impression therefrom.

8. In a device of the class described, in combination, a carriage, and a plurality of balls suspended from said carriage, said balls being adapted to make a distinctive mark upon a recording surface.

9. In a device of the class described, in combination, a carriage, and a plurality of hollow rubber balls suspended from said carriage, said balls being provided with a printing fluid and having means adapted to make a distinctive mark upon a recording surface.

10. In a device of the class described, in combination, a carriage, and a plurality of hollow rubber balls suspended from said carriage by wires, said balls being provided with a printing fluid and having means adapted to make a distinctive mark upon a recording surface.

11. In a device of the class described, in combination, a carriage, and a plurality of hollow rubber balls suspended by wires from said carriage, said balls being arranged in a distinctive configuration and provided with a printing fluid and having means adapted to make a corresponding mark upon a recording surface.

12. In a device of the class described, in combination, a car, a pivotally mounted plate carried thereby provided with a lever and having a plurality of perforations therein, a brake valve adapted to be actuated by said lever, and means interposed in the path of said plate at one side of the pivotal mounting of the same adapted to move said plate so as to actuate said valve.

13. In a device of the class described, in combination, a call box, a carriage, a rock

shaft interposed between said call box and said carriage, an arm fixed upon said shaft and adapted to be actuated by said carriage, and a second arm fixed upon said shaft and 5 adapted to actuate said call box.

14. In a device of the class described, in combination, a call box, a rock shaft adapted to actuate said call box, and a member adapted to rotate about said shaft and co-act 10 with an arm fixed thereon so as to actuate said shaft.

15. In a device of the class described, in combination, a carriage, a printing device suspended from said carriage, a car, and a 15 plate carried by said car having a recording surface adapted to co-act with said printing device.

16. In a device of the class described, in combination, a carriage, a printing device 20 suspended from said carriage comprising a plurality of balls arranged in a distinctive configuration, a car, and a plate carried by said car having a recording surface adapted to co-act with said printing device.

25 17. In a device of the class described, in combination, a carriage, a printing device suspended by wires from said carriage comprising a plurality of balls arranged in a distinctive configuration, a car, and a plate carried 30 by said car having a recording surface adapted to co-act with said printing device.

35 18. In a device of the class described, in combination, a carriage, a printing device suspended by wires from said carriage comprising a plurality of rubber balls arranged in a distinctive right line configuration, a car, and a plate carried by said car having a recording surface adapted to co-act with said 40 printing device and provided with a lever adapted to actuate the braking system of the car.

45 19. In a device of the class described, in combination, a carriage, a printing device suspended from said carriage, a car, a plate carried by said car having a recording surface adapted to co-act with said printing device and provided with a lever adapted to actuate the braking system of the car.

50 20. In a device of the class described, in combination, a movable member, a carriage adapted to travel upon said member as the latter is moved from one to the other of two alternative positions, and a printing device 55 yieldingly suspended from said carriage.

55 21. In a device of the class described, in combination, a lever, a call box mounted adjacent said lever, a carriage adapted to travel upon said lever, and a shaft journaled within said lever and provided with two arms fixed 60 thereon, one of which is adapted to engage and operate said call box and the other of which is adapted to engage and be actuated by said carriage.

65 22. In a device of the class described, in combination, a lever, a call box mounted ad-

jacent said lever, a carriage adapted to travel upon said lever as the latter moves from one to the other of two alternative positions, and a shaft journaled within said lever and provided with two arms fixed thereon, one of 70 which is adapted to engage and operate said call box and the other of which is adapted to engage and be actuated by said carriage.

23. In a device of the class described, in combination, a lever, a carriage adapted to 75 travel thereon as said lever is moved from one to the other of two alternative positions, a printing device suspended from said carriage, a car, and a plate carried by said car having a recording surface adapted to co-act 80 with said printing device.

24. In a device of the class described, in combination, a lever, a carriage adapted to travel thereon as said lever is moved from one to the other of two alternative positions, 85 a printing device suspended from said carriage, a car, a plate carried by said car having a recording surface adapted to co-act with said printing device, and braking mechanism upon said car adapted to be actuated 90 by the impact of said printing device against said plate.

25. In a device of the class described, in combination, a lever, a carriage adapted to travel thereon as said lever is moved from 95 one to the other of two alternative positions, a printing device suspended from said carriage, a car, a plate carried by said car having a recording surface adapted to co-act with said printing device when said carriage 100 is at the outer end of said lever, and braking mechanism upon said car adapted to be actuated by the impact of said printing device against said plate.

26. In a device of the class described, in 105 combination, a car, a plate carried thereon having a recording surface, a carriage, a printing device suspended from said carriage and adapted to be interposed in the path of said plate, and a call box adapted to 110 be actuated by the impact of said printing device upon said plate.

27. In a device of the class described, in combination, a car, a plate carried thereon having a recording surface and provided 115 with means for actuating the braking mechanism of said car, a carriage, a printing device suspended from said carriage and adapted to be interposed in the path of said plate, and a call box, said parts being so arranged 120 that the impact of said printing device upon said plate will apply the brakes of said car and actuate said call box.

28. In a device of the class described, in combination, a lever, a carriage adapted to 125 travel upon said lever as the latter is moved from one to the other of two alternative positions, a printing device suspended from said carriage, a car, a plate upon said car having a recording surface adapted to co-act with 130

said printing device, and a call box mounted adjacent said lever and adapted to be actuated by said carriage as said carriage is moved by the impact of said printing device 5 with said plate.

29. In a device of the class described, in combination, a lever, a carriage adapted to travel upon said lever as the latter is moved from one to the other of two alternative positions, a printing device suspended from said carriage, a car, a pivoted plate upon said car having a recording surface adapted to co-act with said printing device, a lever upon said plate adapted to actuate said 15 brake valve, and a call box mounted adjacent said lever and operatively connected to said carriage so that upon contact of the printing device with the recording surface the plate will be rotated to actuate said 20 brake valve and the carriage will be moved to actuate the call box.

30. In a device of the class described, in combination, a semaphore, a support for the same, a lever pivoted upon said support, and 25 a carriage adapted to travel upon said lever as the latter is moved by said semaphore from one to the other of two alternative positions.

31. In a device of the class described, in combination, a semaphore, a support for the same, a lever pivoted upon said support, a carriage adapted to travel upon said lever as the latter is moved by said semaphore from one to the other of two alternative positions, said carriage being also adapted to rotate about said lever, and a call box adapted to be actuated by the rotary movement of said carriage.

32. In a device of the class described, in combination, a lever, a carriage adapted to travel upon said lever as the latter is moved from one to the other of two alternative positions and adapted to oscillate about the same, a printing device carried by said carriage, a call box mounted adjacent said lever and operatively connected to said carriage and adapted to be actuated by the same as said carriage oscillates about said lever upon the impact of said printing device with a co-acting recording surface.

33. In a device of the class described, in combination, a semaphore, a lever mounted upon the support thereof, a carriage adapted to travel upon said lever as the latter is moved from one to the other of two alternative positions by said semaphore and adapted to oscillate about the same, a printing device carried by said carriage, a call box mounted adjacent said lever and operatively connected to said carriage and adapted to be actuated by said carriage as it oscillates about said lever upon contact of said printing device with a co-acting recording surface.

34. In a device of the class described, in

combination, a lever, a carriage mounted upon said lever and adapted to travel thereon as the lever is moved from one to the other of two alternative positions, a printing device carried by said carriage, a car, a 70 plate mounted upon said car and adapted to co-act with said printing device, and a call box mounted adjacent said lever and operatively connected to said carriage and adapted to be actuated by the impact of said 75 plate against said printing device.

35. In a device of the class described, in combination, a lever, a carriage mounted upon said lever and adapted to travel thereon as the lever is moved from one to the other of two alternative positions, a printing device carried by said carriage, a car, a 80 perforated plate mounted upon said car and adapted to co-act with said printing device, and a call box mounted adjacent said lever 85 and operatively connected to said carriage and adapted to be actuated by the impact of said plate against said printing device.

36. In a device of the class described, in combination, a lever, a carriage mounted 90 upon said lever and adapted to travel thereon as the lever is moved from one to the other of two alternative positions, a printing device carried by said carriage, a car, a 95 perforated plate pivotally mounted upon said car and adapted to co-act with said printing device, a brake valve, a lever upon said plate adapted to actuate said brake valve, and a call box mounted adjacent said first lever and operatively connected to said 100 carriage, said parts being so arranged that upon the interposition of said printing device in the path of said plate and contact therewith the impact will apply the brakes of said car and actuate said call box.

37. In a device of the class described, in combination, a semaphore, a support for the same, a lever mounted upon said support, a carriage mounted upon said lever and adapted to travel thereon as said lever is moved by 110 said semaphore from one to the other of two alternative positions, a plurality of rubber balls suspended from said carriage, a car, and a plate carried by said car, said balls being provided with means for making a distinctive impression upon a recording surface 115 upon said plate.

38. In a device of the class described, in combination, a semaphore, a support for the same, a lever pivotally mounted upon said support, a carriage mounted upon said lever and adapted to travel upon the same as said lever is moved from one to the other of two alternative positions by said semaphore, a car, a pivotally mounted plate carried by 120 said car, an arm upon said plate, a brake valve adapted to be actuated by said arm, a plurality of balls suspended from said carriage and adapted to co-act with said plate 125 so as to leave a distinctive impression upon 130

the surface thereof and actuate the brake mechanism of said car.

39. In a device of the class described, in combination, a semaphore, a support for the 5 same, a lever pivotally mounted upon said support, a carriage mounted upon said lever and adapted to travel upon the same as said lever is moved from one to the other of two alternative positions by said semaphore, a 10 distinctive printing device carried by said carriage, a car, a plate pivotally mounted upon said car, an arm rigidly secured to said plate, a brake valve adapted to be actuated by said arm, a call box mounted adjacent 15 said lever, an operative connection between said call box and said carriage, said parts being so arranged that upon the contact of said printing device with said plate the impact thereof will operate to apply the brakes 20 of said car and actuate said call box.

40. In a device of the class described, in combination, a car, a call box, and means adapted to retard the motion of said car, leave a distinctive mark thereon and actuate 25 said call box.

41. In a device of the class described, in combination, a car, a call box, and means adapted simultaneously to retard said car, leave a distinctive mark thereon and actuate 30 said call box.

42. In a device of the class described, in combination, a car, a signal, a call box, and means adapted to retard said car, leave a mark peculiar to said signal thereon and actuate 35 said call box.

43. In a device of the class described, in combination, a car, a signal, a call box, and means adapted simultaneously to retard said car, leave a mark peculiar to said signal 40 thereon and actuate said call box.

44. In a device of the class described, in combination, a car, a signal, a call box, and means set in operative condition by said signal adapted to retard said car, leave a mark 45 peculiar to said signal thereon and actuate said call box.

45. In a device of the class described, in combination, a car, a signal, a call box, and means set in operative condition by said signal adapted simultaneously to retard said car, leave a mark peculiar to said signal 50 thereon and actuate said call box.

46. In a device of the class described, in combination, a carriage, a printing device 55 yieldingly suspended therefrom, a car, and means upon said car adapted to co-act with said printing device and receive an impression therefrom.

47. In a device of the class described, in combination, a series of printing devices, a car adapted to travel adjacent the same, and means upon said car adapted to co-act with 60 said printing devices and receive an impression therefrom indicative of the place at 65 which the impression was received.

48. In apparatus of the class described, in combination, a car, a series of signals, means adapted upon said car passing one of said signals in danger condition automatically to stop said car, and means adapted automatically to record the stopping of said car and the place at which said car was stopped. 70

49. In a device of the class described, in combination, a car, pivoted means carried thereby and adapted to expose substantially 75 equal surfaces to the air upon each side of its pivot, means connected with first-mentioned means and adapted to be actuated by swinging thereof and upon actuation to apply the brakes of said car, and means interposed in 80 the path of said first-mentioned means and adapted to actuate the same.

50. In a device of the class described, in combination, a car, means carried thereby adapted upon actuation to apply the brakes 85 of said car, and means interposed in the path thereof, said brake applying means comprising a pivotally mounted swinging plate having its axis substantially at the center thereof.

51. In a signaling apparatus, in combination, a series of signals, and means adapted 90 upon a car passing any one of said signals in danger position to give a notice at a distant point indicative of the particular signal which has been passed. 95

52. In apparatus of the class described, in combination, a car, means adapted to transmit a distinctive signal to a distant point, movable means associated with said transmitting means and normally maintained in 100 operative relation thereto, means for moving said last-mentioned means into operative relation with said transmitting means, and means associated with said car to actuate said movable means when in said operative 105 position.

53. In apparatus of the class described, in combination, a car, a series of means each of which is adapted to transmit a distinctive signal to a distant point, movable means 110 associated with each of said transmitting means and normally maintained in inoperative relation thereto, means for moving said last-mentioned means into operative relation with its associated transmitting means, and means associated with said car to actuate 115 any one of said movable means when in said operative position.

54. In apparatus of the class described, in combination, a car, actuating means associated therewith, means adapted to transmit a distinctive signal to a distant point, means for operating said transmitting means, said operating means being normally out of the path of travel of said actuating means, 120 and means for moving said operating means into the path of travel of said actuating means. 125

55. In apparatus of the class described, in combination, a car, actuating means as- 130

sociated therewith, a series of signals, calling means associated with each of said signals to coact with said actuating means upon the car passing said signal when in danger position, 5 each of said calling means being adapted to transmit to a distant point a call indicative of its associated signal, whereby a person at said point will know which signal has been passed.

10 56. In apparatus of the class described, in combination, a car, a series of signals, means adapted upon a car passing any one of said signals in danger position to automatically record the particular signal passed.

15 57. In apparatus of the class described, in combination, a car, a record receiving device associated therewith, a signal, a recording device associated therewith and adapted to coact with said receiving device when the 20 signal is at danger, said recording device being indicative of its associated signal.

25 58. In apparatus of the class described, in combination, a car, means associated with said car adapted to receive an impression thereon, a signal, and means associated with said signal to make a distinctive impression upon said first means upon said car passing said signal when set to indicate danger.

59. In apparatus of the class described, in combination, a car, means associated with 30 said car adapted to receive an impression thereon, a signal, and means associated with said signal to make an impression indicative of its associated signal upon said first-mentioned means upon said car passing said 35 signal when set to indicate danger.

60. In apparatus of the class described, in combination, a car, means associated with said car adapted to receive an impression thereon, a series of signals, and means associated with each of said signals to make an impression upon said first-mentioned means upon said car passing any one of said signals when set to indicate danger, each of said 40 second means being adapted to make an 45 impression indicative of the signal with which it is associated, whereby an impression made upon said first means will indicate which particular signal is passed.

In testimony whereof I affix my signature, 50 in the presence of two witnesses.

SAMUEL H. HARRINGTON.
